UNITED STATES PATENT OFFICE.

ANSON MILLS, OF WASHINGTON, DISTRICT OF COLUMBIA.

SEAMLESS WOVEN CARTRIDGE-POCKET.

SPECIFICATION forming part of Letters Patent No. 787,851, dated April 18, 1905.

Application filed July 30, 1904. Serial No. 218,939.

To all whom it may concern:

Be it known that I, ANSON MILLS, of the United States Army, retired, a citizen of the United States, and a resident of Washington city, in the District of Columbia, have invented a new and useful Improvement in Seamless Woven Cartridge-Pockets for Containing Cartridges or other Articles, of which the following is a specification.

The characteristic of the pocket is that it is a seamless multi-ply woven-fabric pocket the several plies of which constitute, respectively, the front and back walls of the pocket as well as an interior partition which forms a division-wall between the front and rear walls of the pocket.

The pocket may be woven on and integral with a belt or bandoleer, or it may be woven separately and subsequently connected to its support by any suitable means. It may be used as a cartridge-carrier, and this is its main purpose; but it can also be employed as a receptacle for any desired articles, and its size and dimensions may be varied according to the load it is intended to carry. It can be used, for example, as a haversack or the like.

In the drawings accompanying and forming part of this specification, to which reference will now be made for a better understanding of my invention, Figure 1 is a perspective view of a double pocket embodying my invention. Fig. 2 is a cross-section of the same on line 2 2, Fig. 1. Fig. 3 is a longitudinal section of one of the pockets on line 3 3, Fig. 1. Fig. 4 is a diagrammatic sectional representation of the three plies, showing where they merge into one another to form the body fabric and where they branch off to form the several component parts of a pocket.

There is a line between two adjoining plies wherever they are together, but this is only to define the plies.

The particular pockets shown in the drawings are designed to hold each four clips of five cartridges, or twenty cartridges in all, two clips in each division of the pocket. In each division of the pocket the two clips are placed one heads up and the other points up, so as to occupy the least possible space and to lie in compact mass.

The side edges *a* of the fabric, as well as the portion *b* of the fabric intervening between the two pockets, may be considered the body fabric, in this instance a three-ply woven fabric. In weaving a pocket one ply, the inner 55 ply, will be used for the back wall *c*, the intermediate ply will be used for the partition *d*, and the outer ply will be used for the front wall *e*. In starting to weave a pocket the inner ply will be used for the back wall *c*, while 60 the other two plies will be thrown into one of the side walls of the pocket, as at *f*, until the point is reached at which the partition *d* is to be formed. At this point one of the two plies (the intermediate) is thrown into the 65 partition, while the other (the outer ply) continues in on the remainder of the side, as at *f'*, and thence in front of the wall *c* of the pocket. The weaving thus continues until the other side of the pocket is reached, when 70 the three plies are successively again consolidated and merged into the body fabric, the outer ply continuing on a portion of the side until it meets the point where it joins the intermediate ply, the two merging together to 75 form the remainder of the side of the pocket, until finally they join with the back ply to form again the body fabric. The fullness which allows the formation of the side walls of the pockets, as well as the gathering in and 80 closing of the pocket at its bottom, is obtained substantially in the manner set forth in patent to T. C. Orndorff, No. 666,687, of January 29, 1901.

The body fabric typified at *a a* may be extended any desired length as a belt or bandoleer and may be provided with as many pockets as desired, or I can weave the pockets separately or in groups and then provide them with means for attaching them to a 85 belt or other support—as, for example, the double pocket shown in Fig. 1 has metallic clips *g* passing through eyelet-holes *h* in the body fabric and provided with inner hook ends adapted to catch over the edges of a belt. 90

The pockets are preferably provided with suitable fabric covers *i*, held closely by glove-fasteners *k*, and for additional security, cross-straps *l* for holding down the cover-flaps may be employed. The straps are con- 95 100

veniently formed of a webbing secured at its center to the middle clip *g* and having its loose ends adapted to stretch over across the covers and thence down on the sides of the 5 pockets, where they are secured by glove-fasteners *m*.

The arrangement of the metallic clips and of the secured straps I do not claim as my invention.

10 What I do claim herein as new and of my own invention is—

A seamless multi-ply woven-fabric pocket, having an internal partition formed of an intermediate ply which extends between the

side walls of the pocket and merges into the 15 same, said side walls being formed for a portion of their breadth of the conjoined plies which enter into the partition and the front wall of the pocket, respectively, and, for another portion of their breadth, of the ply 20 which enters into the front wall of the pocket, substantially as hereinbefore set forth.

In testimony whereof I affix my signature in presence of two witnesses.

ANSON MILLS.
